UNITED STATES PATENT OFFICE.

GIOVANNI DANOVARO, OF WELLAND, ONTARIO, CANADA.

TORPEDO-GUARD.

1,270,020.

Specification of Letters Patent. Patented June 18, 1918.

Application filed March 12, 1917. Serial No. 154,396.

To all whom it may concern:

Be it known that I, GIOVANNI DANOVARO, a subject of the King of Italy, residing at Welland, Ontario, Canada, have invented 5 certain new and useful Improvements in Torpedo-Guards, of which the following is a clear, full, and exact description.

My invention relates to improvements in torpedo guards, more especially to torpedo 10 guards for use on ships. The object of my invention is to provide a torpedo guard which shall effectively prevent a torpedo from damaging the hull of the vessel. To this end I provide means whereby the tor- 15pedo will be either diverted entirely from its course or else be caused to explode at some distance from the hull of the vessel, the impact of the explosion being prevented by appropriate means from reaching the 20 hull of the vessel.

In the drawings, Figure 1 is a side elevation of a vessel equipped with my invention;

Fig. 2 is an end view of the same;

Fig. 3 is a fragmentary plan view of one 25 side of the vessel with the deck broken away;

Fig. 4 is a side view in elevation of one of the movable screens;

Fig. 5 is a side view in elevation of the 30 stationary screen or shield; and

Fig. 6 is an end view of parts shown in Fig. 3 illustrating a motor in connection therewith.

From each side of the hull of the vessel 1 35 project a number of rotatable shafts 3. A set of shafts is arranged at each side of the vessel, at the bow and at the stern. The outer ends of the shafts of each set are connected by a bar 5, which forms an ex- 40 tension of a member 6 having its inner end attached to the vessel to form a bracket for the shafts.

Adjacent the outer end of each shaft is a crank 7. Connecting these cranks 7 on 45 each side of the vessel is a frame 8 loosely secured to the outer ends of the cranks by rings or the like 9. Stretched on the frame and secured thereto is a net 10; this net is preferably formed of small ropes 11. Be- 50tween this crank 7 and the hull of the ship, each shaft is provided with a crank 12 set at 180° from the crank 7, and mounted on these cranks 12 at each side of the vessel is a frame 13 similar to the frame 8 in every respect. The inner ends of the shafts 3 extend through the hull and are operatively

connected, by chains 21 and sprockets 23, to a motor 14 of any desired type, by which they may be caused to rotate.

Between the frame 13 and the hull of the 60 vessel, a third frame 15 is mounted on the shafts to slide longitudinally thereof. On this frame are secured a plurality of slabs of cork 17 to form a continuous sheet or wall. Between the frame 15 and the hull 65 of the vessel are provided a plurality of compression springs 19.

The frames 8, 13 and 15, together with the nets and slabs of cork carried thereby, 70 form screens or shields for protecting the hull of the vessel from torpedo attack. The device is so arranged that the nets have their upper ends approximately flush with the water line, and extend downwardly far enough to protect the vital parts of the ves- 75 sel. The position of the nets along the sides of the vessel is such as to bring them in the probable paths of any torpedo fired at the vessel.

The rotation of the shaft 3 causes the 80 frames 8 and 13 to oscillate in their own planes, parallel to each other, but since the cranks 7 and 12 are set at an angle of 180°, the movements of these frames will be out-of-phase so as to produce a continual change 85 in the relative positions of the frames. If the torpedo reaches the outer net 10, the meshes of which are of course considerably smaller than the cross-section of the torpedo, it will be slowed up to a certain degree 90 but will, however, probably pass entirely through the net. However, while it is passing through the net, the oscillatory move- 95 ment of the latter acting successively along different portions of the length of the tor-pedo will not only tend to deflect the tor-pedo considerably from its path, but will also still further decrease its speed. The passage of the torpedo through this net will break a greater or less number of the 100 strands, and the dangling ends of these will tend to catch in the propeller of the tor-pedo; even if this does not result in completely stopping the forward movement of the torpedo, such forward movement will 105 be considerably reduced and the course of the torpedo changed.

The effect of the second net in neutralizing the forward movement of the torpedo will, however, be increased by the fact that 110 it is moving in a direction opposite to that of the first net. It is to be understood, of

course, that the shafts 3 will be rotated at a comparatively low speed so that a torpedo that passes through both nets will reach the second one while it is still moving 5 in a direction opposite to that in which the outer or first net is moving at the time of the passage of the torpedo therethrough. Should a torpedo get safely past both nets without entanglement of the propeller, it 10 will strike the cork slabs 17 on the inner frame. This will usually cause the torpedo to explode, but since the great effectiveness of cork as a shock absorber is supplemented by the springs 19, the force of the explosion 15 will do little more than force the frame 15 inwardly toward the hull of the vessel.

While I have described and shown in the drawings a preferred form of my invention, it is to be understood that I am not limited 20 to the specific details disclosed, but in practical use may adapt such modifications as come within the scope of the appended claims.

What I claim is:—

- 25 1. A torpedo guard comprising a net and means for imparting to the net a continuous oscillatory motion in its own plane.
2. A torpedo guard comprising a plurality of nets positioned one in front of the other 30 for interposition in the probable paths of torpedoes, and means for imparting to each of said nets a continuous oscillatory movement in its own plane.
3. A torpedo guard comprising a plurality 35 of members one in front of the other for interposition in the probable paths of torpedoes, and means for moving said members out-of-phase so as to produce a continual change in the relative positions of 40 said members.
4. A torpedo guard comprising a plurality of vertical screens throughout their extent lying in parallel planes, and means for producing a relative movement of said screens 45 in said planes.
5. In combination with the hull of a vessel, a plurality of relatively movable screens mounted on the side of the vessel, certain of said screens adapted to permit the pass-

sage therethrough of a torpedo but to deflect it from its course, another of said screens arranged to receive the impact of a torpedo and of its explosion. 50

6. In combination with the hull of a vessel, a plurality of rotatable shafts extending therefrom, a net mounted on said shafts adjacent the outer ends thereof and parallel to the side of the vessel, a second net on said shafts between the vessel and the first net, cranks on said shafts by which the 60 nets are connected thereto, the cranks for the first net being set at an angle to the cranks for the second net, whereby the rotation of the shafts causes said nets to move in their planes relative to the vessel and to 65 each other, and an elastic shield resiliently supported between said nets and the side of the vessel.

7. In combination with the hull of a vessel, a plurality of vertical frames arranged 70 along the side of the vessel, one beyond the other, the outer frames carrying nets and being mounted for movement in their planes out-of-phase with each other, the inner frame having cork slabs mounted thereon 75 to form a continuous wall, and compression springs between said inner frame and the side of the vessel.

8. In combination with the hull of a vessel, a plurality of vertical frames arranged 80 along the side of the vessel longitudinally thereof and positioned one beyond the other, the said frames carrying nets and having out-of-phase movements to produce a continual change in the relative positions of 85 said nets.

9. In combination with the hull of a vessel, a plurality of vertical frames arranged along the side of the vessel longitudinally 90 thereof and positioned one beyond the other, the said frames carrying nets and having out-of-phase parallel movements to produce a continual change in the relative positions of said nets.

Signed at New York, N. Y., this 27th day 95 of February, 1917.

GIOVANNI DANOVARO.
